(57) **CLAIM**

We claim the ornamental design for a stand for a portable electronic device, as shown and described.

DESCRIPTION

FIG. 1 is a perspective view of the stand for a portable electronic device according to the present invention.

FIG. 2 is a front view of the stand for a portable electronic device of FIG. 1.

FIG. 3 is a rear view of the stand for a portable electronic device of FIG. 1.

FIG. 4 is a bottom view of the stand for a portable electronic device of FIG. 1.

FIG. 5 is a top view of the stand for a portable electronic device of FIG. 1.

FIG. 6 is a left side view of the stand for a portable electronic device of FIG. 1.

FIG. 7 is a right side view of the stand for a portable electronic device of FIG. 1; and,

FIG. 8 is another perspective view thereof.
